US00D535312S

(12) **United States Design Patent** (10) **Patent No.:** **US D535,312 S**
Simpson, III (45) **Date of Patent:** **** Jan. 16, 2007**

(54) **CUTTING INSERT**

(75) Inventor: **Vandell E. Simpson, III**, Akron, OH (US)

(73) Assignee: **Manchester Tool Company**, Akron, OH (US)

(**) Term: **14 Years**

(21) Appl. No.: **29/255,915**

(22) Filed: **Mar. 14, 2006**

Related U.S. Application Data

(63) Continuation of application No. 29/220,318, filed on Dec. 29, 2004, now abandoned.

(51) **LOC (8) Cl. 15-09**

(52) **U.S. Cl. D15/139**

(58) **Field of Classification Search** D15/138, D15/139; 407/35, 42, 112-119

See application file for complete search history.

(57) **CLAIM**

The ornamental design for a cutting insert, as shown and described.

DESCRIPTION

FIG. 1 is a perspective view of a cutting insert showing my new design;

FIG. 2 is a side elevational view of the cutting insert shown in FIG. 1;

FIG. 3 is a top plan view of the cutting insert shown in FIG. 1;

FIG. 4 is a bottom plan view of the cutting insert shown in FIG. 1.

FIG. 5 is a left end view of the cutting insert shown in FIG. 1; and,

FIG. 6 is a right end view of the cutting insert shown in FIG. 1.

The broken lines in FIGS. 1-6 are for illustrative purposes only and do not form part of the invention shown in FIGS. 1-6.

1 Claim, 2 Drawing Sheets
